UNITED STATES PATENT OFFICE

2,637,005

CONTROL FOR SCREEN EXCITING
OSCILLATOR

Charles N. Hood II, Schenectady, and William S. Oakes, Jr., Pattersonville, N. Y., assignors to General Electric Company, a corporation of New York

Application January 4, 1952, Serial No. 264,942

5 Claims. (Cl. 315—364)

1

This invention relates to a control for a screen exciting oscillator, and in particular to an improved control for regulating the intensity of illumination of the fluorescent coating on the screen of cathode ray tubes.

Cathode ray tubes having fluorescent coatings are so constructed that upon proper electrical excitation the screen will glow. In order for a tube of this sort to have a uniform glow intensity and hence a picture of even contrast, it is necessary that the tube screen be uniformly coated with the fluorescent material.

It has been found that visual observance under low conditions is a satisfactory method of checking the uniformity of the fluorescent coating. For such a test, it has been found that approximately 20 foot-candles of light should be produced by the glow surface, and this light intensity is constant for tubes of all sizes and under all vacuum conditions.

A suitable glow exciting device is an electrode which when positioned at the focal point of the tube and when properly excited by a vacuum tube power oscillator produces a corona discharge, which under suitable vacuum and voltage conditions causes the entire fluorescent surfaces of the tube to glow with a uniform intensity.

In a cathode ray tube assembly line, a station is provided for checking the uniformity of the fluorescent coating. At such a station there might appear tubes of the same size, not held at the same vacuum, or tubes of various sizes, e. g. 0", 16" or 30". Both size of the tube and the vacuum conditions within it affect the power required for a suitable glow. Accordingly, it would not be possible with any one setting on the test equipment to maintain at a fixed level the light intensity for tubes of various sizes and vacuums.

It is an object of this invention, therefore, to provide a new test apparatus or device wherein the light intensity at the fluorescent surface is maintained constant and uniform irrespective of the vacuum conditions and the size of the tube.

It is a further object of this invention to provide a new test device for fluorescent coatings on tubes wherein the power output of an oscillator is responsive primarily to the light intensity on the face of the tube.

It is a still further object of this invention to provide an improved light sensitive device for varying the power output of a vacuum tube oscillator.

Further objects and advantages of this invention will become apparent and the invention will

2

be more clearly understood from the following description, referring to the accompanying drawings, and the features of novelty which characterize this invention will be pointed out with particularity in the claims annexed to and forming a part of this specification.

While for the purpose of clarity this description is limited to cathode ray tubes, it is obvious that this invention is applicable to any surface which is made fluorescent as a result of an electrical stimulus, and it is to be understood that the example of the cathode ray tube is not intended as a limitation, but rather has it been chosen merely as an illustration to bring forth more clearly the operating principles and features of this invention.

Briefly, this invention comprises an apparatus including a power oscillator for illuminating the screen of a cathode ray tube and a light sensitive unit operating in response to the light intensity at the tube screen to vary the voltage output of the power oscillator.

In the drawing, Fig. 1 is a front elevation, partly in section, of a cathode ray tube positioned in a test stand and schematically connected to an electric circuit for causing its fluorescent surface to glow; Fig. 2 is a block diagram showing a system for controlling the light intensity at a fluorescent surface; Fig. 3 is a simple schematic diagram showing in greater detail the circuit shown in the block diagram of Fig. 2.

In the drawings, a cathode ray tube 1 is shown positioned in a test stand 2 having a vacuum outlet or aperture 3, a bottom sealing cork 4, and an electrode 5 having one end 6 positioned at the focal point of tube 1. Electrode 5 is energized by a vacuum tube oscillator-amplifier 7 which in turn is responsive to a signal from a light sensitive device 8.

Cathode ray tube 1 is of the conventional type having a curved face surface 9 coated on the inside with a fluorescent layer 10. Tube 1 is cone-shaped and tapers down to an open neck 11 through which the tube can be evacuated.

Under a suitable voltage and vacuum condition, the electrically charged tip 6 of electrode 5 produces a corona discharge at the focal point of the tube. The corona ionizes the gas remaining in the tube, and the fluorescent coating 10 is made to glow uniformly over the whole curved surface 9.

Tube 1 is evacuated by positioning it in a flange 12, a portion of stand 2 which has a resilient ring 13 made of a rubberlike material. Ring 13 is positioned at the upper end of holder

12, and it is shaped to grip the side walls of the cathode ray tube 1 to provide a leak-free seal. A vacuum source is then connected to aperture 3 to bring down the pressure within tube 1 and holder 12 to about 20-40 microns.

In order to produce the glow discharge within tube, electrode 5 is positioned so that its tip 6 extends through cork 4 up into the neck of the tube. Since the bottom of stand 2 is sealed by a rubber cork or stopper 4, a tube 1 is lowered into the stand 2 so that its neck 11 passes over and encompasses the electrode 5. The electrode 5 is so held that its elevation may be varied to position tip 6 at the focal point of tubes of different sizes, or near the average focal point of several different size tubes.

Electrode 5 is then electrically connected to the power output coil of a suitable high voltage oscillator-amplifier 7, which can produce at tip 6 a potential in the order of 30,000 to 50,000 volts R. M. S. at about 25 kilocycles. A voltage of this range will produce a glow discharge at the fluorescent surface 10 of a 30" television picture tube when it has been evacuated to 20-40 microns.

In order to comprehend the requirements of the voltage range under varying tube sizes and vacuum conditions, it should be understood that for a glow intensity of 20 foot-candles approximately 20,000 volts should be impressed at the focal point of a 12-inch tube at 40 microns. At 60 microns, for the same tube a potential in the order of 33,000 volts might be required. So, too, if the size of the tube is increased while the vacuum conditions are constant, the glow voltage must be increased. It is to be understood, however, that in an assembly line usually it is not feasible to pump down all tubes to exactly the same vacuum. Consequently, for simplicity of control, it is desirable to be able to vary the power output of the oscillator to compensate for any vacuum variations or tube size variations.

To compensate for the variance in vacuum conditions, tube size, and other possible factors; i. e.,

1. Sensitivity of the type of phosphor 10,
2. Aluminized backing of phosphor 10,
3. Water molecules in the residual gas,
4. Temperature effect on ionization of the residual gas,
5. Light conductivity of tube face 9,

the voltage output at the tip of 6 of electrode 5 must be increased as either the vacuum or tube size is increased. This invention, therefore, relates to a unique device which automatically compensates the voltage potential at the tip 6 of the electrode 5 in response to the light intensity at the face of the cathode ray tube.

The primary elements of this device are schematically shown in the block diagram of Fig. 2 wherein it is indicated that a master signal is produced by the master oscillator 14, which signal is applied to a variable gain amplifier. Photoelectric cell 8 actuates a photoelectric amplifier 15 which produces a signal that modifies the gain of the variable gain amplifier and, consequently, the signal from the variable gain amplifier which controls the output of a power amplifier 7.

While we do not intend to limit ourselves to any particular circuit for varying the power oscillator output in response to the light intensity at the fluorescent screen of the cathode ray tube, one simple circuit is shown schematically in Fig. 3 wherein the master oscillator 14 comprises a

resonant circuit 17 coupled to the input of a tube 18 which generates in the plate circuit thereof a high frequency constant amplitude alternating current voltage. This voltage is impressed on a grid 20 of the variable gain amplifier tube 16 by conductor 19.

The variable gain amplifier in response to the voltage of conductor 19 impresses an amplified high frequency voltage on conductor 21 which is connected to the grid 22 of the power amplifier tube 7 to operate the same; i. e., power amplifier 7 produces a voltage proportional to the signal on conductor 21 which is connected to the grid 22. The direct current component of voltage in the output circuit of tube 16 is prevented from controlling the conductivity of the amplifier 22 by a suitable blocking capacitor 21a. The output of power amplifier 7 is impressed on the electrode 6 by means of an output transformer 23 having the secondary winding tuned to the operating frequency of the oscillator 14. The output of plate circuit of the amplifier 7 is completed through the primary winding of transformer 23 and a suitable plate supply 24.

From the foregoing description, it is apparent that the electrode 8 is energized by a high frequency voltage having an amplitude dependent upon the gain of the variable gain amplifier 16. In accordance with an important aspect of our invention, the gain of amplifier 16 is automatically controlled in response to the intensity of illumination at the face of the cathode ray tube 1 to maintain that light intensity at a constant predetermined value. In accordance with the illustrated embodiment of our invention, this control is accomplished by energizing a second control grid 25 of the variable gain amplifier 16 in accordance with the amplified output of the photoelectric device 8. The photoelectric device is coupled to the control member 26 of the photoelectric amplifier 15 to provide with resistor 27 a voltage dividing circuit connected across the plate supply battery 28 of the amplifier 15. As the intensity of illumination at the cathode ray tube screen increases, the resulting increased conductivity of the photoelectric device 8 renders the control member 26 of amplifier 15 more positive. The resulting increase in the conductivity of amplifier 15 renders the plate thereof more negative. Since the control member 25 of the amplifier 16 is coupled directly to the plate of amplifier 15, the more negative voltage of the plate reduces the gain of the amplifier 16 with a resulting decrease in the power supplied by the master oscillator to the electrode 6. Conversely, a decrease in the light intensity at the surface of the cathode ray tube decreases the conductivity of amplifier 15, renders the plate thereof more positive, which in turn impresses a more positive voltage on the control member 25 of the variable gain amplifier to increase the power supplied to the electrode 6.

This equipment is such that irrespective of conditions within the tube to be tested, the light intensity automatically adjusts itself so that approximately 20 foot-candles of light appear on the surface 10 of tube 1.

It is obvious that this improved equipment is a great feature in assuring proper quality control of the fluorescent coating on cathode ray tubes. It assures, automatically, a uniform tube illumination in such a manner that the speed of inspection can be greatly increased.

Of incidental interest is the fact that a battery 30 and a manually controlled rheostat 31

can be connected through double-throw switch 32 to the grid 25 of the variable gain amplifier to impress a voltage on it for calibration purposes, or manual control of tube illumination.

Modifications of this invention will occur to those skilled in the art, and it is desired to be understood, therefore, that this invention is not intended to be limited to the particular embodiment disclosed, but rather is it intended to cover all modifications which are within the true spirit and scope of this invention.

What we claim as new and desire to secure by Letters Patent of the United States is:

1. A test stand for checking the uniformity of a fluorescent coating on the inner surface of a cathode ray tube comprising means for supporting a cathode ray tube, means for evacuating said tube, means for illuminating the face of said tube and control means for regulating the degree of power supply to said illuminating means, said illuminating means comprising an electrode having a tip at the focal point of said cathode ray tube, a power oscillator for energizing said electrode, said control circuit comprising a photoelectric tube positioned to be responsive to the light intensity at the face of said cathode ray tube and a variable gain amplifier operable in response to a signal from said photoelectric tube to vary the power output of said power oscillator, thereby to maintain uniform the light intensity of the face of said cathode ray tube.

2. A device for checking the uniformity of light intensity at the face of a cathode ray tube having a fluorescent coating on its inner surface, said device comprising an electrode having a tip positioned at the focal point of said tube, circuit means including a power amplifier for energizing said electrode and a variable gain amplifier for controlling the output of said power amplifier, a photoelectric tube positioned to be responsive to the degree of light intensity at the face of said cathode ray tube, and control means including a photoelectric amplifier operable in response to said photoelectric tube for changing the output of said variable gain amplifier thereby to control the output of said power amplifier in the voltage at said electrode.

3. Apparatus for producing a predetermined light intensity at the face of a cathode ray tube

50

having a fluorescent screen on the inner surface thereof, said apparatus comprising an electrode, support means for supporting a cathode ray tube with said electrode extending into the interior thereof, circuit means including a power oscillator for impressing a voltage of variable magnitude on said electrode, a photosensitive control means positioned to be responsive to the light intensity at the face of a cathode ray tube carried by said support means, and control means operable in response to said photosensitive control means for controlling said circuit means to maintain the voltage at said electrode at the magnitude required to produce said predetermined light intensity.

4. Apparatus for producing a predetermined light intensity on a fluorescent screen, said apparatus comprising an electrode for activating said screen to illuminate the same, circuit means including a power oscillator for energizing said electrode, and control means for varying the degree of energization of said electrode.

5. Apparatus for producing a predetermined light intensity on a fluorescent screen, said apparatus comprising an electrode for activating said screen to illuminate the same, circuit means including a power oscillator for energizing said electrode, control means for varying the degree of energization of said electrode, said control means comprising a photosensitive element positioned to be responsive to the light intensity of said screen, and means operable by said photosensitive element for varying the output of said power oscillator inversely to the degree of illumination of said screen.

CHARLES N. HOOD II.
